(57) **CLAIM**

We claim the ornamental design for a slider for slide fastener, as shown and described.

DESCRIPTION

FIG. 1 is a front elevational view of a slider for slide fastener of the claimed design.

FIG. 2 is a rear elevational view of the slider for slide fastener of FIG. 1.

FIG. 3 is a top plan view of the slider for slide fastener of FIG. 1.

FIG. 4 is a bottom plan view of the slider for slide fastener of FIG. 1.

FIG. 5 is a right side elevational view of the slider for slide fastener of FIG. 1, the left side view being a mirror image; and,

FIG. 6 is a perspective view of the slider for slide fastener of FIG. 1.
